(57) **CLAIM**

The ornamental design for a light emitting diode, as shown and described.

DESCRIPTION

FIG. 1 is a rear top right side perspective view of a light emitting diode showing our new design;

FIG. 2 is a front, bottom, left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The portions shown in black indicate the color black. The portions shown in white, i.e., the thin square portion surrounding the center top window in FIGS. 1 and 5 and the two small circles in FIGS. 2 and 6 indicate the color white. The center top window inside the thin white portion in FIGS. 1 and 5 is shaded to indicate that it is translucent. The electrodes are shaded to indicate contour.

The thin white portion is substantially planar and flush with the surrounding black body portions. The center top window is substantially planar and flush with the surrounding thin white portion and black body portions. The two small white circles of FIGS. 2 and 6 are substantially planar and flush with the surrounding black body portions.
